UNITED STATES PATENT OFFICE.

CARL SCHLÜNS, OF THURINGIA, GERMANY, ASSIGNOR TO MERCEDES BÜRO-MASCHINEN- UND WAFFENWERKE, OF POST MEHLIS, GERMANY.

TYPEWRITER.

Application filed January 17, 1921. Serial No. 437,985.

(GRANTED UNDER THE PROVISIONS OF THE ACT OF MARCH 3, 1921, 41 STAT. L., 1313.)

To all whom it may concern:

Be it known that I, CARL SCHLÜNS, a citizen of Germany, residing at Zella-Mehlis 2, Thuringia, Germany, have invented certain new and useful Improvements in Type-writers (for which I have filed applications in Germany May 11, 1914, Patent No. 319,752, and on April 2, 1918), of which the following is a specification.

10 This invention relates to improvements in the manner of supporting type-bars for type-writers.

15 In the hitherto known typewriters, in which the type-bars swing upon a circular arc, the type-bars stand in the position of rest, and either lie horizontally, or are suspended vertically. They form therefore, in their position of rest, an angle of 90° or 180° with their point of contact upon the platen.

20 In the position of 90°, the type-bars must all be of a certain length, which is limited by the construction of the machine and the standard width of type. The length of the type-bars is however so dimensioned that 25 very soon fluttering and recoiling-strokes of the type-bars set-in, in consequence of which unclear and obliterated writing is produced.

25 If the types are allowed to swing through 180°, the type-bars will either be so short, that a solid support is impossible, or the type-bars must be extended so far, that the advantage to be gained by the extension of the angle, is once more lost.

30 All these disadvantages are eliminated by the present invention, if the radius of the axis of oscillation of the type-bars is selected about $\frac{2}{3}$ the vertical height of the lower position of type bar rest from the platen striking point. The following advantages are thereby achieved:

35 1. A considerable shortening of the type-bars for equal width of the type-bar-heads.
2. A displacement of the center of gravity and the torsional moment towards the bar-bearing.

40 3. In consequence of shortening of the type-bars, a generally more compact and lower construction of the machine.

45 4. Elimination of all flattening and recoiling strokes during writing.

50 5. Omission of the type-bar guide-head and consequently also omission of subsequent

adjusting of the type-bars by hand, as the type-bars can be used in the condition in which they come from the bending-press.

55 6. In consequence of shortening the type-bars require easier touch control, more rapid action of the types ensues, independent of accuracy for the side-guide of the type-bars in the supporting segment.

60 7. A considerable reduction in first-cost of the machine in consequence of a more rational production of the type-bars without special machinery.

65 The considerations by which the correctness of the invention is proved, are illustrated in the annexed drawings of which.

70 Figs. 1 and 2 show the arrangement according to the invention.

75 Figs. 3 and 4 are illustrations provided for comparison purposes.

The angle β , with which two type-bars are placed with respect to each other depends upon the length and width of the type-heads. Both are fixed dimensions, since a certain standard for type-writing has been introduced. Usually the type bar in standard machines is supported, so that it describes an angle of 90° from the position of rest with respect to the printing point. If a bar of half the length should be selected so that the aforesaid angle should be 180°, the angles γ formed by the single-bars at the printing-point c , would be of the same value, for the same space provided for the type-bar heads. The position of rest of the type-bars would be in the first case at h , in the second case at b , Fig. 6.

80 85 If at the same angle β at the printing point the distance of the type-blocks from each other is still taken as standard, and the length of the type-bars is altered, all possible positions of the type-blocks will still remain on the line $a-a$. The position and angle of the fulcrum center β and the trajectory belonging thereto, are correspondingly altered.

90 95 4 cases are consequently possible:
1. $\beta_1 = 90^\circ$ (Fig. 4) standard machine.
2. $\beta_1 = 180^\circ$ (Fig. 4) machine with a support of the type-bars with an angle of 180°.
3. $\beta_1 < 90^\circ$ (Fig. 4).
4. $\beta_1 > 90^\circ$, but < 180° (Fig. 4) idea of the invention.

Case 1.

Supposing:

$$r=ah=75 \text{ mm.}, \beta_1=90^\circ;$$

then follows that

$$\text{arc } ch : 2r\pi = \beta_1 : 360.$$

$$\text{arc } ch : \frac{2r\pi \cdot 90}{360}$$

$$10 \quad \text{arc } ch = \frac{2.75 \cdot 3.1416 \cdot 90}{360}$$

$$\text{arc } ch = 117.8 \text{ mm.}$$

Case 2.

Supposing:

$$= 180^\circ$$

$$r=ce=1/2.75 \text{ (case 1)} = 37.25 \text{ mm.}$$

then

$$20 \quad \text{arc } ch : 2r\pi = \beta_2 : 360.$$

$$\text{arc } ch = \frac{2r\pi \cdot 180}{360}$$

$$25 \quad \text{arc } ch = \frac{37.25 \cdot 3.1416 \cdot 180}{360} = 117.8 \text{ mm.}$$

Case 4.

Supposing:

$$\beta_4=120^\circ$$

$$r=cd=49.5 \text{ mm.}$$

then

$$30 \quad \text{arc } cg : 2r\pi = \beta_4 : 360.$$

$$\text{arc } cg = \frac{2r\pi \cdot 120}{360}$$

$$35 \quad \text{arc } cg = \frac{49.5 \cdot 3.1416 \cdot 120}{360}$$

$$\text{arc } cg = \frac{180}{180}$$

$$\text{arc } cg = 103.6 \text{ mm.}$$

- 40 The case 3 is of no interest, as it is the most unfavourable. It is thus shown, that in standard machines, in which the type-bar is 75 mm. and the angle of swing 90°, the circular trajectory which the type-block will have to describe will be 117.8 mm. This is the case as for type-writers, in which the angle of swing is 180° and the type-block trajectory would still be 117.8 mm.

- 45 The vertical suspension of the bars at 180° offers therefore no advantage as the trajectory distance remains the same. But at an angle of swing $\beta=120^\circ$ and a radius=49.5 mm. for the circular arc, the value 103.6 mm. for the trajectory is obtained, viz. a difference 55 compared to cases 1 and 2, of 14.2 mm. or 12% of the distance, which the type-blocks have to pass over.

- 50 All circular trajectories the centers of which are located on the line $e-a$ produce 60 smaller trajectory values from the printing point c . The most favorable case, viz. the shortest trajectory for the type-block, is theoretically found to be for a radius (length of bar) $r=42$ mm. and an angle of 65 swing $\beta=140^\circ$ appertaining thereto.

The difference between the circular trajectories resulting from the radii 49.5 mm. and 42 mm. with the angles of swing 120° and 150° respectively, is however very small; it is only noticeable for a second position 70 shift of the plates and amounts only to 0.05 mm. as the following calculation shows.

If $\beta=120^\circ$, $r=49.5$ mm., then

$$75 \quad \text{arc } cg = \frac{49.5 \cdot 3.1416 \cdot 120}{180}$$

$$\text{arc } cg = 103.67 \text{ mm.}$$

If $\beta=180^\circ$, $r=42$ mm., then

$$80 \quad \text{arc } \frac{140^\circ}{180} = 42 \cdot 3.1416 \cdot 140$$

$$\text{arc } \frac{140^\circ}{180} = 103.62 \text{ mm.}$$

difference thus = 0.05 mm.

In practice it is preferable, to select a 85 length of type-bar and an angle of swing, which approximate to the most favourable condition viz. the shortest circular trajectory without neglecting the other requirements for producing a robust machine.

The present invention relates to type-writers with slot-guides, whereby the bars are guided in slots of a cast-iron segment and whereby the important exchangeability 90 of single type-bars is retained.

In order to meet the last requirement, a working-lever has to fit the slot of the type-bar in such wise, that between the bars sufficient space is left for the working-lever 100 and the rivet belonging thereto.

The tongues, which remain between the 105 slots of the segment, have likewise to be strong enough, so that they do not bend during milling of the segment. The thickness of the type-bar itself should not be more than 1 mm. as its strength is otherwise impaired.

In consideration of all these requirements it has been found in practice that an angle 110 of 100 to 120° will be most favourable for a given length of type-bar. The length of the projection $\alpha=Kg$, which the circular trajectory cuts off at a radius r about the point d , from the ordinate axis is found by 115 the formula

$$\sin 30^\circ = \frac{\alpha}{r}$$

therefore, as

$$r=49.5 \text{ mm.}$$

120

is,

$$\alpha = \sin 30^\circ \cdot 49.5$$

$$\alpha = 24.725 \text{ mm.}$$

125

as the most favorable ratio suitable for practice.

The above specification is based upon my prior application Ser. No. 35675 filed June 22nd, 1915.

130

What I claim as my invention and desire to secure by Letters Patent, is:

1. In a typewriting machine of substantially standard proportions in which the standard vertical distance of approximately 75 mm. is maintained between the printing point of the type heads and the nesting point of the type heads, a platen, and a type bar, the length of said type bar being substantially two-thirds the vertical distance of the nesting point of the type heads from the printing point, said type bar being so mounted with respect to said platen as to swing through an arc substantially more than 100° and less than 140°.
- 15 2. In a typewriting machine of substan-

tially standard proportions in which the vertical distance of approximately 75 mm. is maintained between the nesting point of the type heads and the printing point, a platen and a type bar, said type bar being 20 so mounted with respect to said platen that it has an angle of swing from rest of substantially more than 130° and less than 140°.

In testimony whereof I affix my signature 25 in presence of two witnesses.
